COLLAR CLASP

Richard Karl Boog, Newark, N. J.

Application October 25, 1937, Serial No. 170,927

2 Claims. (Cl. 24—81)

My invention relates to improvements in clasps, or clips, for securing the wings of collars together against displacement from curling and other causes.

5 The primary object of the invention is the provision of an inexpensive device of this character which may be more quickly and easily applied than the present day clasps of commerce and which will securely hold the collar in desired 10 position without tearing or otherwise mutilating the same.

Other, and subordinate objects, are also comprehended by my invention, all of which together with the precise nature of my improvements 15 will be readily apparent when the following description and claims are read with reference to the drawing accompanying and forming part of this specification.

In the said drawing:—

20 Figure 1 is a view in front elevation of my improved clasps,

Figure 2 is a view in longitudinal section taken on the line 2—2 of Figure 1, and

Figure 3 is a view in rear elevation.

25 Referring to the drawing by numerals, in the preferred embodiment of my invention illustrated in the drawing, the clasp thereof comprises a front jaw member 1, of suitable light metal, having the form of an elongated shell including an outwardly bowed front wall 2, inwardly curved ends 3 and side walls 4. The side walls 4 are provided on each side of the transverse center thereof adjacent to said center with a pair of opposed ear-like extensions 5. The 30 back of the clasp is formed by a pair of similar shell-like jaw members 7 and 8, each comprising a rear wall 9, a curved outer end 10 and side walls 11. The members 7 and 8 are disposed end-to-end with the side walls 11 and ends 10 mating with the side walls 4 and ends 3 of the member 1 in clamping relation thereto at opposite ends of the member 1 respectively. The 35 pair of jaw members 7 and 8 are pivoted, as at 11', to the pairs of extensions 5, respectively, intermediate their ends for relative movement to swing the same into and from clamping relation to the member 1. The adjacent ends of the jaw members 7 and 8 are pivoted together by means of a pair of elliptical or elongated eye members 40 12 and 13 formed on said ends, respectively, and a pivot pin 14 extended loosely through said eye members and held against endwise movement by the side walls 11 of one of said members. A pair of tension springs 15 are interposed between the 45 50 55 front walls 2 and the adjacent ends of the mem-

bers 7 and 8 upon opposite sides of the pivot pin 14, respectively, and between said pin and the pivots 11', respectively, whereby the members 7 and 8 are tensioned against movement from clamping relation to the member 1. The mating side walls 4 and 11 and the ends 3 and 10 are serrated, as at 16, to facilitate gripping the collar, not shown, therebetween, the serrations being rounded to obviate tearing of the collar. Suitable keepers 17 on the member 1 and the members 7 and 8 anchor the springs 15 in location. Preferably the keepers 17 take the form of a pair of opposed yoke like members one secured to the inner face of the jaw member 1 and the other adapted to straddle the elliptical eye members 12 and 13 and fit around the same against the inner faces of the members 7 and 8, in detached relation thereto, so as not to interfere with the movement thereof.

As will be clear, by grasping the described 20 clasp between two fingers and thumb of one hand with the fingers against the member 1 and the thumb against either, or both, members 7 and 8, intermediate the pivots 11', and exerting the required pressure on said members, the jaw members 7 and 8 may be swung simultaneously against the tension of the springs 15 out of clamping 25 relation in the desired degree. The ears of the collar may then be inserted between the members 1 and 7 and 8 and pressure released whereupon 30 the members 7 and 8 will snap into clamping relation to member 1 simultaneously.

The construction, operation and advantages of 35 my invention will, it is believed, be clear from the foregoing without further explanation.

Manifestly the invention, as described, is susceptible of modification without departing from the inventive concept and right is herein reserved to such modifications as fall within the scope of the claims appended hereto.

What I claim is:—

1. A clasp for collars comprising a front jaw member, a pair of rear jaw members pivotally mounted intermediate their ends on the front jaw member in end-to-end position for relative swinging movement into and from clamping relation with respect to the opposite ends of the front member, respectively, a pivotal sliding connection between adjacent ends of said pair of members compensating for relative swinging movement thereof and connecting said members together, said connection comprising a pair of elongated eye members on said ends, respectively, and a pin extending through said eye members, 45 50 55

and means tensioning said pair of members against movement from clamping relation.

5. A clasp for collars comprising a front jaw member, a pair of rear jaw members pivotally mounted intermediate their ends on the front jaw member in end-to-end position for relative swinging movement into and from clamping relation with respect to the opposite ends of the front member, respectively, a pivotal sliding connection between adjacent ends of said pair of members compensating for relative swinging movement thereof and connecting said members together, said connection comprising a pair of

elongated eye members on said ends, respectively, and a pin extending through said eye members, and means tensioning said pair of members against movement from clamping relation and comprising a pair of opposed yokes one fixed to 5 the front jaw member opposite said eye members to extend upon opposite sides of the latter, and the other spanning said eye members and slidably engaging the same and the adjacent ends of said pair of jaw members, and a pair of tension springs interposed between opposed ends of the said yokes.

RICHARD KARL BOOG.
